UNITED STATES PATENT OFFICE.

HARRY HOLLINGS, OF EDINBURGH, SCOTLAND.

AUTOMATIC SHEET-SEPARATING DEVICE FOR PRINTING, FOLDING, AND LIKE MACHINES.

1,179,832.

Specification of Letters Patent. Patented Apr. 18, 1916.

Application filed August 26, 1914. Serial No. 858,624.

To all whom it may concern:

Be it known that I, HARRY HOLLINGS, of 23 Warrender Park Terrace, Edinburgh, in the county of Midlothian, Scotland, a subject of the King of Great Britain and Ireland, have invented new and useful Improvements in Automatic Sheet-Separating Devices for Printing, Folding, and like Machines, of which the following is a specification.

My said invention relates to sheet separating devices for printing, folding and like machines, and has for its object to provide means whereby the objectionable separation and removal, from a pile, of more than one sheet at a time is greatly reduced or eliminated.

In carrying out my invention the separating devices consist of a disk and stop or the like which advance for a short distance over the surface of the top sheet of a pile, the disk being provided with a rubber or other frictional surface. The disk and stop after advancing a predetermined distance over the sheet, have imparted to them a simultaneous reciprocating movement, at right angles to the direction in which they are advanced, whereby that part of the sheet between the disk and stop is rucked or doubled up from the remaining sheets of the pile. A separating finger, suitably carried, is now advanced and is interposed between the rucked or doubled up portion of the sheet and the sheet immediately below. The sheet is now ready to be removed from the pile, and for this purpose it is preferred to employ the automatic suction sheet feeder, referred to in my earlier Patent 942036, which grips and lifts the sheet from the side, or end, at which it is rucked or doubled up, the disk and stop hereinbefore referred to being simultaneously withdrawn from the sheet. The separating devices are duplicated, and adapted to operate near each side or end of the sheet.

In order that my said invention and the manner of performing the same may be properly understood I hereunto append a sheet of explanatory drawings to be hereinafter referred to in describing my invention.

Figure 1, is a back elevation of a part of a printing machine provided with my improved automatic sheet-separating devices. Fig. 2, is a side elevation, and Fig. 3, is a

side and back elevation of one of the separating fingers, drawn to a larger scale.

In these drawings the same reference numerals are used to mark the same or like parts wherever they are repeated.

As shown in the drawings the separating devices consist of a disk 1, and stop 2, adjustably fixed on a rocking shaft 3, said shaft being connected through a link 4, to, and operated by levers 5, said levers having connection with the opposite ends of the roll 7 and loose connection with the links 4 as shown in Fig. 2 of the drawings while at the same time carrying the automatic suction roll 7, referred to in my earlier Patent 942036. The shaft 3, is loosely supported in, and connected by, brackets 8, 9, to a fixed shaft 10, that is, the shaft 3 is supported to slide or translate in bearings at the lower ends of the brackets 8 and 9 suspended or hung from the fixed shaft 10, and torsion or tension springs 11, 12, are fitted to the shaft 10, in connection with the brackets 8, 9, so as to facilitate the rocking movement of the shaft 3. On the brackets 8, 9, there are also fixed cross bars 13, 14, these cross bars limiting the outward travel of the shaft 3, by coming in contact with stops 15, 16, fixed on the shaft 10, while at the same time the levers 5, can complete their travel, independently of the links, each connecting link 4, being provided with an elongated slot 17, for this purpose. To the inner end of the rocking shaft 3, there is fixed a bracket 18, connected by a spring 19, to the shaft 10, and on one end of the bracket there is mounted a roller 20, free to rotate, said roller being adapted to work against a plate 21, having an inclined surface, whereby as the shaft 3, moves outward it is slightly turned so as to raise the disk 1, and stop 2, off the sheet, and as the shaft 3, returns, the spring 19, reverses the turning movement of the shaft so that the disk 1, and stop 2, are depressed into contact with the sheet which is to be rucked.

The rocking shaft 3, has imparted to it a reciprocating movement through a bellcrank lever 22, rod 23, and a second bellcrank lever 24, the latter being operated by a cam 25, on a shaft 26. The inward movement of the shaft 3, compresses a spring 27, and the reaction of this spring returns the shaft 3, when released from the bellcrank lever 22.

Two separating fingers 28, 29, carried on rods 30, 31, bracketed to a shaft 32, rocked through a lever 33 operated by a cam 34, on the shaft 26, are interposed between the 5 rucked parts of the sheet and the pile, so as to prevent the remaining sheets being disturbed or lifted by the suction roll 7.

In operation the action of my improved sheet-separating devices is as follows:—The 10 disk 1, and stop 2, are adapted to press on the top sheet of a pile, the disk 1, being provided with a rubber or other frictional bearing surface, while the stop 2, has a smooth surface. When the shaft 3, carrying 15 the disk 1, and stop 2, is moved inward across the sheet, by the bellcrank lever 22, a ruck 35, is formed on the sheet, by the disk 1, drawing it inward, the stop 2, simply sliding over the sheet and serving to limit 20 the distribution of the ruck, whereby the latter will be elevated the proper degree and the projection of the finger therebeneath insured. After the ruck 35, has been formed, as just described, the bellcrank lever 25 22, is released and the separating fingers 28, 29, advance and rest on the pile immediately below the rucked portions of the sheet. The suction roll 7, is now advanced to grip the sheet, and at the same time the disk 1, and 30 stop 2, through the connecting link 4, and inclined plate 21, are respectively drawn off and raised clear of the sheet, the latter being gripped by a pair of feed rolls, not shown. Immediately after the rucked sheet 35 is lifted by the suction roll 7, the disk 1, and stop 2, return and press on the next sheet, after which the separating fingers 28, 29, are withdrawn, and this sheet is now rucked. 40

By the use of my invention all risk of more than one sheet being removed, at a time, is greatly reduced or eliminated, and any liability of the remaining sheets being disturbed is avoided, as each sheet is removed 45 at the side or end at which it is rucked and separated, and the remaining sheets are held in position by the separating fingers, 28, 29, and disk 1, and stop 2. Further, by removing the sheets at the side or 50 end at which they are rucked and separated, allows of different sized sheets being manipulated without the objectionable necessity of adjusting the devices to suit the size of the sheets.

55 What I claim is:—

1. In an automatic sheet separating device, a swinging shaft, a buckling device mounted and on said shaft and adapted to engage a sheet of a pile, a holding member 60 mounted on said shaft in adjustable spaced relation with said buckling member and adapted to coöperate therewith, means for imparting a longitudinal movement to said shaft and causing said members to buckle said sheet, means for further separating

said buckled sheet from the pile, and means for swinging said shaft whereby said members disengage said buckled sheet.

2. In automatic sheet separating devices for printing, folding and like machines, a 70 movable shaft, a buckling device mounted on said shaft and adapted to engage a sheet of a pile, a holding member mounted on said shaft in adjustable spaced relation with respect to said buckling member and adapted to coöperate therewith, means for imparting movement to said shaft for causing said member to buckle said sheet, means for removing the sheet from the pile after thus buckled and means for moving said shaft whereby to disengage the members from the buckled sheet.

3. In automatic sheet separating devices for printing, folding and like machines, means for rucking a sheet at independent 85 points spaced apart, means for shifting said rucking means at right angles to the direction of rucking movement to contact with the top sheet of a pile, and means for sliding said rucking means in a rectilinear path 90 at right angles thereto and in a constant plane parallel to the sheet for rucking the same to permit its removal.

4. A mechanism for separating and singly removing sheets from a pile includ- 95 ing a plurality of simultaneously operable means movable in two directions at right angles to raise the top sheets of a pile to permit displacement thereof, swinging cam operated means for actuating said last-mentioned means, the latter means being operable in opposite directions in moving toward and away from the sheets.

5. A mechanism for separating and singly removing sheets from a pile includ- 105 ing means operable in two directions at right angles toward each other to ruck the top sheets of a pile whereby to permit the displacement thereof, stops mounted upon a common support with said rucking means 110 and coöperatively movable therewith to frictionally engage the sheets at spaced distances from the rucking means to positively effect the rucking of the sheets, and suction means for removing the sheets so 115 rucked.

6. A mechanism for separating and singly removing sheets from a pile includ- 120 ing means operable in two directions at right angles to ruck the top sheets of a pile, said means including an oscillatory shaft, means for moving the same, stops adjustably mounted on the shaft to engage the sheets at spaced distances from the rucking means, said stops being adjustable toward 125 and away from the rucking means to regulate the length and elevations of the rucks, and means for removing the sheets thus rucked and separated.

7. A machine for automatically separat- 130

ing singly, the exposed sheets of a pile comprising a plurality of rucking means operable on a horizontal pivot to move into and out of contact with such sheets, spring operated shifting means for said rucking means whereby to permit the return of the latter out of contact with respect to the sheets, means for shifting the rucking means in opposite directions and in a constant plane parallel to the sheets to be rucked whereby to ruck the latter at two points, angular fingers simultaneously operable to separate the sheets thus rucked at the rucked portions thereof from the sheets therebeneath, suction means coöperatively associated with the shifting means for the rucking means to remove the sheets thus separated and rucked from the pile, said fingers preventing the removal of additional sheets with said rucked and separated ones.

8. A machine for automatically separating singly, the exposed sheets of a pile com-

prising a rocking shaft, a suction roll having compensating link connections with said rocking shaft, a fixed shaft, brackets supporting said rocking shaft, means for limiting the rocking movement of the shaft, spring means holding said rocking shaft under tension in an inoperative position, stops mounted on said rocking shaft, rucking disks also adjustably mounted on said shaft, spring operated camming surfaces for shifting said rucking means into operative position, rollers at the inner ends of the shaft or shafts for engagement thereby and a lever engageable with the ends of the shaft for shifting the latter longitudinally in any position of the path of its movement.

In testimony whereof I have signed my name to this specification in the presence of two subscribing witnesses.

HARRY HOLLINGS.
